KEY CONTAINER

Norman E. Olson, San Diego, Calif.

Application July 9, 1945, Serial No. 603,765

4 Claims. (Cl. 70—456)

1

My invention relates to key containers, particularly transparent pocket receptacles for the carriage and use of keys, and its objects are to furnish a means for nesting a set of keys and for permitting the projection or extrusion therefrom of the blades of said set and the selection of the blade required for use; to provide a transparent key container of attractive appearance through the walls of which the position and character of the keys may at all times be observed; to afford a non-collapsible covering of some elasticity but of sufficient rigidity to preserve and hold the shape of the container; to ensure durability of all parts of the container and to guard against the effects of grease, moisture, mildew, rust and other injurious matter; to dispense with the necessity of using snap buttons or zippers and to avoid stumbling for keys; to permit the container readily to be assembled or disassembled as occasion may require and to allow ready repairs and replacements, and generally to simplify and render more effective the operation of the several parts. Other objects will appear from the drawing and as hereinafter set forth and described.

My invention primarily consists in the provision of a key container having an elastic or resilient casing of sufficient rigidity to preserve and hold its shape and being provided with an ejector forming a septum and closure end of said casing and being hingedly mounted within and upon the walls thereof and serving to turn outwardly and extrude the blades of the keys pivotally nested in said container.

My invention also consists in constructing the walls of said container of glass, transparent plastic or other suitable transparent material through which may be observed at all times the position and nature of the keys carried in said container, and in so shaping and contouring said container as to give the same an artistic and attractive appearance.

My invention further consists in other improvements, novel features of construction, combination and arrangements of parts, illustrated in the drawing, and more particularly hereinafter described and claimed.

Attention is hereby directed to the drawing, illustrating a preferred form and modification of my invention, in which similar numerals of designation refer to similar parts throughout the several views, and in which—

Figure 1 is a plan view of a preferred form of my invention showing a casing with a transparent wall through which may be observed the ejector closure septum and all but one of the keys of the

2

set nested in normal position within said casing, the blade of the remaining key being shown out of said casing and in extended position;

Fig. 2 is a plan view of the transparent container illustrated in Fig. 1, except that all the blades of the set of keys are shown in the process of being extruded from the casing through the operation of the ejector closure septum;

Fig. 3 is a plan view of the transparent casing shown in Fig. 1 with the set of keys and ejector closure septum removed therefrom, and showing various openings, stops and recesses therein the purpose of which will hereinafter be explained;

Fig. 4 is a plan view of the ejector closure septum, showing the same removed from the transparent casing;

Fig. 5 is an end view of the ejector closure septum shown in Fig. 4 looking at the same from the left;

Fig. 6 is an end view of the casing shown in Fig. 3;

Fig. 7 is a plan view of a modification of my improved key container, showing a transparent casing with two sets of keys and two ejector closure septa therefor in closed position, and Fig. 8 is a plan view of the container shown in Fig. 7, with the blade of one key projected therefrom and the blade of another key in the process of being extruded from said container.

Referring to the drawing, Figs. 1 to 6: Within the hollow 19 of the casing 10, formed of two spaced plates 11 and 12 disposed in parallel relation and connected by a bridge 13, I install a key or set of keys 14; the said key or set of keys being pivotally connected within and to the walls at the front end of said casing by the screw or bolt 15, engaging with passageways 16 in said walls and passing through the usual openings in the base of said keys. At the rear and opposite end portion of said casing, and within the walls thereof is located the ejector closure septum 17, hingedly connected to said walls by the pin 19 extending through an opening in said septum and through openings 18 in said walls provided therefor. As will be observed, the septum 17 is U-shaped to conform with the contour of the edge of the adjoining walls at this portion of said casing and to fill the space therebetween, and serves when in the closed position shown in Fig. 1 to

act as a closure for such portion of the casing, the lower end or lobe 20 of said septum being bevelled underneath and shaped to make close contact with the inclined seat 21 of the bridge 13, and to rest thereon. Also, I preferably pierce the upper end or lobe 22 of said septum with a

rod, the extended ends of which form catch buttons 23, which effect releasable engagement with cup shaped depressions 24 in the adjoining inner walls of the casing, the said walls being sufficiently resilient to allow such engagement. As shown in Fig. 1, the said lower end 26 of the septum 17 is made of sufficient length and of such shape as to make ready contact, when turned upwardly upon the pin 19, with the lower edges of the blades of the keys 14 to raise such blades out of the casing 10 so that their ends may be grasped and selection made therefrom of the key desired for use. If desired, stops 25 may be affixed to the inner walls of said casing to limit the turning movement of the septum 17, and also a cut out 26 may be provided for admission of a thumb or finger nail to contact the upper end 22 of the ejector closure septum 17 and to raise the same to extrude the blades of the keys 14.

In Figs. 7 and 8, I have shown a modification of the key container shown in Figs. 1 to 6, to accommodate two sets of keys, the casing 27 of this modification being somewhat enlarged for the purpose, and two ejector closure septa 28 and 29 of special construction being provided for the extrusion of the blades of the keys. Also two bridges 30 and 31 for connecting the spaced plates of the casing 27 are shown instead of a single bridge as shown in the other structure; the said bridges acting also as stops for said septa. To ensure compactness, the inner ends of said septa 28 and 29 are located so as to be seated one against the other, when in the normal position shown in Fig. 7; but otherwise said septa are hingedly mounted upon the walls of the casing 27, acting to eject the blades of the keys, are provided with releasable contacts, serve as closures and also as a means for retrieving the blades to the inside of the case, and are similar to and operate the same as my other key container.

In both these preferable forms of my improved key container, as illustrated in the drawing, I have shown all parts thereof as transparent except the screws or bolts 15, and for such parts I preferably use transparent plastic or glass, or any suitable material capable of transmitting rays of light so that the contents of said container can be clearly seen, and at the same time affording a non-collapsible covering of some elasticity resiliency but being of sufficient rigidity to preserve and hold the shape of the container. However, while such transparency is desirable for the full exercise of my invention, nevertheless a very wide range of opaque materials otherwise suitable might be employed in the construction of my improved key container and excellent results secured; and therefore except as limited in the appended claims, I do not desire the scope of my invention to be limited solely to the use of transparent parts.

The two types of containers shown in the drawing complement each other, and when used in conjunction, one with the other, will serve to hold and carry all the keys which the ordinary person would find it necessary to carry. The single set type would hold the keys for the car, and the double set would hold the keys for the house, garage, safe deposit box, padlocks and the like. These containers are easily opened or closed, and there is no fumbling for the right key; the selection of keys being rendered easy and rapid. There are no snap buttons or zippers that require both hands to operate as is the case with a leather container. Also my containers are

of durable materials and will hold their shape indefinitely, and they are not harmed by grease or water or mildew or other destructive agents that affect leather.

5 My invention may be embodied in other specific forms without departing from the spirit or essential characteristics thereof. The present embodiment, as above set forth, is therefore to be considered in all respects as illustrative and not restrictive, the scope of my invention being indicated by the appended claims rather than by the above description, and all changes which come within the meaning and range of equivalency of the claims are therefore intended to be embraced therein.

What I claim and desire to secure by Letters Patent is:

1. A key container, comprising two transparent spaced plates connected and maintained in 20 parallel relation by a bridge affixed thereto and conforming to the adjacent edges thereof, means for pivotally securing a key or keys to and between said plates at one end portion thereof, and a U-shaped ejector septum pivotally connected 25 to and extending between said plates at the opposite end portion thereof and normally acting to seat its lower lobe upon said bridge and substantially to close the space between said plates, but at the same time being operable to project the 30 blades of said keys out of and to return said blades to the space between said plates.

2. A key container, comprising two transparent spaced plates connected and maintained in parallel relation by a bridge affixed thereto, the 35 outer edge of said bridge extending to and conforming with the adjacent outer edges of said plates, means for pivotally securing a key or keys to and between said plates at one end portion thereof, and a U-shaped septum pivotally connected 40 to and extending between said plates at the opposite end portion thereof and operable to project or retract the blades of said keys and with said bridge normally serving upon said projection or retraction substantially to close the 45 space between said plates, and said bridge having an inclined seat within said space shaped to receive, and upon which normally rests, the lower lobe of said septum.

3. A key container, comprising two transparent plates connected and maintained in parallel relation by a bridge affixed thereto, the outer edge of said bridge extending to and conforming with the adjacent edges of said plates, and the inner walls of said plates having cup shaped 55 depressions therein clear of said bridge, means for pivotally securing a key or keys to and between said plates at one end portion thereof, and a U-shaped septum pivotally connected to and extending between said plates at the opposite end 60 portion thereof and operable to project or retract the blades of said keys and with said bridge normally serving upon said projection or retraction substantially to close the space between said plates, and catch buttons affixed to the upper 65 lobe of said septum and situated to make releasable engagement with said cup shaped depressions.

4. A key container, comprising two transparent spaced plates connected and maintained in parallel relation by a bridge affixed thereto, the outer edge of said bridge extending to and conforming with the adjacent outer edges of said plates, and the inner walls of said plates having cup shaped depressions therein clear of said 70 bridge, means for pivotally securing a key or keys

75

to and between said plates at one end portion thereof, and a U-shaped septum pivotally connected to and extending between said plates at the opposite end portion thereof and operable to project or retract the blades of said keys and with said bridge normally serving upon said projection or retraction substantially to close the space between said plates, catch buttons affixed to the upper lobe of said septum and situated to make releasable engagement with said cup shaped depressions, and said bridge having an inclined seat within said space shaped to receive and upon which normally rests the lower lobe of said septum.
